MACHINE FOR EVACUATING AND SEALING CONTAINERS

Reid A. Mahaffy, Cedar Grove, William E. Young,
Ramsey, and John R. Harder, Cedar Grove, N. J., as-
signors to Standard Packaging Corporation, Chicago,
Ill., a corporation of Virginia

Application November 26, 1954, Serial No. 33,260

Term of patent 14 years

(Cl. D55—1)

Fig. 1.

Fig. 2.

Fig. 3.

Fig. 4.

Figure 1 is a front elevational view of a machine for evacuating and sealing containers showing our new design.

Figure 2 is a side elevational view of the machine shown in Figure 1.

Figure 3 is a rear elevational view of the machine shown in Figure 1.

Figure 4 is a top plan view of the machine shown in Figure 1.

We claim:

The ornamental design for a machine for evacuating and sealing containers, substantially as shown.
